DANIEL SHERWOOD AND GEORGE D. DUDLEY, OF LOWELL, MASSACHUSETTS.

Design No. 4,297, dated August 16, 1870.

DESIGN FOR A TABLE-CASTER.

The Schedule referred to in these Letters Patent and making part of the same

We, DANIEL SHERWOOD and GEORGE D. DUDLEY, of the city of Lowell, in county of Middlesex and State of Massachusetts, have invented and produced a new and original Design for a Table-Caster, of which the following is a specification.

The nature of our design is fully represented in the accompanying photographic illustration, to which reference is made.

General Description.

The frame of the caster is composed, mainly, of two wires, of the required size and length, twisted together, so as to form the outer caster-ring A and handle, when it diverges at C, to form the legs or feet. Additional wires are laid on at the junction of the legs and handle at C, and twisted together, so as to keep the legs of proper size, or the legs may be wound with wire, if desired.

The bottle-rings D are made of twisted wire, and bent in circular shape.

The rings and legs are united together by a tin-plate center-piece, which is pressed out by dies of the proper shape, and is also provided with ears or straps, which clasp the rings. The legs are inserted in holes in the plate the desired distance before they are bent outward to their proper shape, as shown.

There are ornamental pieces or rosettes, e, placed over the legs, as shown in the drawing, which may be held to the legs in any known way.

Within the outer ring A is another ring, a, which may be of wire, wound upon a ring, and the periphery may be grooved, so as to be held by the ring A.

The whole is then dipped in molten metal, and thereby soldered and tinned at one operation.

A table-caster thus made is highly ornamental in appearance.

It will be obvious that the caster may be made for any number of bottles, say three or five, and still retain the same general appearance, and we intend to make them for a greater or lesser number of bottles, as the market may demand.

Claim.

We claim as our invention—

The design for a table-caster, substantially as shown in the accompanying photographic drawing.

DANIEL SHERWOOD.
GEORGE D. DUDLEY.
